UNITED STATES PATENT OFFICE.

HELEN VINCENT READER, OF ROOSEVELT, WASHINGTON.

DESIGN FOR A DOLL.

Application filed June 13, 1922. Serial No. 2,651. Term of patent 14 years.

To all whom it may concern:

Be it known that I, HELEN V. READER, a citizen of the United States of America, residing at Roosevelt, in the county of Klickitat and State of Washington, have invented a new, original, and ornamental Design for a Doll, of which the following is a specification, reference being had to the accompanying drawings, forming a part hereof.

The figure is a plan view showing my design for dolls.

I claim:—

The ornamental design for a doll as shown.

HELEN VINCENT READER.

In the presence of:—

S. B. WARREN,
W. N. READER.
